GARMENT

Maud L. Rieffannacht, New York, N. Y., assignor
to Kumfitted Garments, Inc., New York, N. Y., a
corporation

Application May 27, 1932, Serial No. 613,810

8 Claims. (Cl. 2—83)

This invention relates to garments of the one-piece variety having a body portion and integral or permanently attached leg portions, and this invention relates more particularly to a concealed

5 utility seat or opening for such garments.

It has heretofore been necessary for a wearer of a garment of the above type to practically disrobe for utility purposes; and the advantages of the new and improved utility seat and opening 10 embodied in my invention will be obvious. In carrying out this invention, I provide a utility seat which is normally perfectly concealed, but which offers immediate and ample accessibility and convenience for utility purposes without any necessity of disrobing, or of even disturbing the 15 fastenings or parts of the garment which are or may be provided for facilitating the donning and doffing of the same.

One object of my invention is to provide a utility seat for one-piece garments, such as sport-suits, bathing suits and pajamas, which may be particularly adapted for sport wear, evening wear, sleeping, lounging or for ordinary wear about the house, by girls or young ladies as a 25 school costume, or other one-piece girl's or lady's garment, other than under-garments, having integral or permanently connected body and leg portions.

A further object of my invention is to provide 30 a utility seat or internal construction for such a one-piece garment so that even when made of thin or transparent material, the garment may be worn without underclothing.

With these and other objects in view the invention consists in the novel construction and arrangement of parts hereinafter described, illustrated in the accompanying drawings, and particularly pointed out in the appended claims, it being understood that various changes in the

40 form and construction may be made without departing from the spirit of the invention or sacrificing any of the advantages thereof.

In the drawings:

Figure 1 is a front view of a pajama garment 45 embodying my invention, partly broken away, and showing in full and in dotted lines the construction of my improved utility seat or inner portions.

Figure 2 is a back view of a garment similar to that of Fig. 1, but showing a modified form of inner part and waist-attachment for the inner portions.

Fig. 3 is a detail side view of part of a garment 50 showing the inner parts in dotted lines.

Fig. 4 is a detail view of the inner part removed from the garment.

Fig. 5 is a back view of a knitted bathing suit made with a seat according to my invention.

Figs. 6 and 7 are plan views showing two modified forms of waist attachment for use according to my invention, and showing the body portion of the garment, at the waist line, in cross-section.

Referring particularly to Fig. 1 of the drawings, the lady's pajamas here shown consist of a body 65 portion 1 and integral leg portions 2. The garment is or may be fastened by means of snaps or the like 3 on an open shoulder seam. An inner member or crotch shield 4 comprising front and back pieces 6, 7, is permanently attached to 70 the front by the line of stitching 5 along the waist line of the body portion 1, and along the upper edge of the front piece 6. The front and back pieces both extend for a short distance downward into the leg portions 2 and the back portion

7 may be of substantially the same shape as the front portion 6, but is slightly fuller and is wider along its top edge than said front portion. These portions 6 and 7 are permanently attached together at their lower ends (see Fig. 4) by a lateral 80 seam 30 corresponding approximately with the inside leg seam 31 of the leg portions 2, and are attached by snap fasteners 8 to the crotch of the garment and by similar fasteners 9 to the inside 85 seams 31 of leg portions 2. At its top edge the back portion 7 is sewn to a belt 10 which passes 90 through eyelets 11 in the body portion 1 and is secured at the front of the body by means of a buckle 32. Snap fasteners 12 on the belt 10 and corresponding sockets 13 on the garment are provided for fastening the ends of the belt when it is desired to use the utility seat and in order that the belt ends may not be lost through the said eyelets 11.

Referring to Fig. 2, in the form shown the inner shield 4 is attached permanently to the back of the body portion 1 by a line of stitching 33, (instead of to the front thereof as in Fig. 1), and strings 14 are in this form adapted to pass through eyelets 11 and to be tied externally of the garment 95 at the rear thereof.

Referring now to Fig. 3, the inner or crotch shield 4 is here shown in dotted lines and the double dotted line extending from X to X represents the extent of a slit or opening 15 (see also 105 Figs. 1 and 2) which is provided in the crotch seam 34 of the garment. It will be observed that this slit 15 is approximately horizontal and disposed directly between the limbs, and hence is quite inconspicuous. At each extremity of this slit 110

one edge thereof is preferably lapped slightly over the other and sewn in this relation in order to predispose said edges to hang closely together or in overlapping relation throughout the full extent 5 of the slit.

Referring particularly to Fig. 4, which shows the crotch shield 4 in detail, it will be noted that this is made up of four pieces of material which are cut and fitted together so as to conform to the 10 wearer's body, limbs and posterior, the sections of the front piece 6 being sewn together along a vertical central seam 16, while the sections of the back piece 7 are sewn together along a central seam 35, and the lower edges of the pieces 6, 7 15 are connected to each other by the lateral crotch seam 30.

Fig. 5 shows my improved utility seat applied to a knitted bathing suit, the crotch shield 4 being permanently attached interiorly at the 20 waist line in front along the line 5. The rear upper edge portion of said crotch shield is extended into a belt 10 which emerging from eyelets 11 encircles the waist of the wearer and is fastened in front by means of a buckle or the like 12.

Referring to Figs. 6 and 7, the belts 18 and 19 respectively shown are for the purpose of giving the effect of a continuous waist-encircling belt while at the same time being interiorly attached to and supporting the upper edge of the crotch 25 shield 4. The belt 18 (Fig. 6) is fashioned of one continuous strip of material joined at its ends, and extending through eyelets 36 in buckle members 37, the inner portion of the belt passing through the eyelets 11 and being attached to the 30 upper back edge of the crotch shield 4, while the outer portion completely encircles the waist of the wearer externally as shown. The belt 19 (Fig. 7) is similar to the belt of Fig. 6, except that it is permanently fixed to the buckle parts 37 at 35 each end of the outer part, while the interior part of the belt which supports the crotch piece 4 is permanently attached at 20 at each end to the outer part.

Although the drawings and the above specification disclose the best modes in which I have contemplated embodying my invention, I desire to be in no way limited to the details of such disclosure, for in the further practical application of my invention, many changes in the construction and 50 in the details may be made as circumstances may require or experience suggest without departing from the spirit of the invention within the scope of the appended claims.

What I claim is:

1. In a combination garment of the class described, a utility seat comprising an interior crotch shield permanently fixed to and extending downwardly from the waist line in front, between the limbs, and upwardly to an exteriorly 60 inaccessible free edge at the back waist line and adapted to be adjustably secured upon the wearer's body, detachable waist-encircling means on said free edge adapted to be exteriorly fastened to adjust and secure said interior shield in 65 wearing position, seams in said shield intersecting each other at the crotch and shaping said shield to the contours of the body, means for concealing said crotch shield, and a slit opening formed in said concealing means, extending between points remote from the waist of the garment and following a substantially horizontal line when the garment is worn upon an erect figure.

2. In a combination garment of the class described, a utility seat portion comprising normal-

ly concealed separable outer parts with approximately horizontal edges meeting at the central crotch line and terminating at points remote from the waist of the garment, an interior shield permanently fixed at one end to the garment 80 at the waist line thereof and dependent therefrom, detachable fastening means on the opposite end of said shield to secure same in wearing position at the waist line opposite to said fixed end on the body of the wearer, seams in said shield intersecting each other at the crotch and shaping said shield to the contours of the body, and detachable fastening means on said shield and on the interior of said separable outer parts to hold same and said crotch piece in fixed relation when the garment is worn.

3. In a combination garment of the class described, a utility seat, comprising a longitudinally and transversely seamed inner back, front and crotch shield free at one of its upper edges and 85 shaped to the body and having downwardly tapering front and rear portions attached together at their lower ends, means on said end for securing the shield in wearing position, outer means for concealing said shield, a slit opening 90 formed in said concealing means, extending between points remote from the waist of the garment and following a substantially horizontal line when the garment is worn upon an erect figure, and concealed fastening means for securing 95 said opening.

4. In a combination garment of the class described, a utility seat comprising edges separable along the horizontal central line and normally concealed entirely between the limbs of the 100 wearer, an interior crotch shield integral at one end with the garment and adjustably suspended from its other end on the wearer's body, seams in said shield intersecting each other at the crotch and shaping said shield to the contours of the 105 body, means on said edges cooperating with means on the shield for securing the former, and means adjacent said edges cooperating with means on said shield for securing the latter in 110 wearing position.

5. In a combination garment of the class described, a utility seat comprising normally concealed edges separable along the central approximately horizontal line entirely between the limbs of the wearer, an interior back, front and crotch shield integral at one end with the waist of the 115 garment and adjustably suspended from its other end on the wearer's body, seams in said shield intersecting each other at the crotch and shaping said shield to the contours of the body, means 120 on said separable edges cooperating with means on the shield for securing the edges together, and means adjacent said edges cooperating with means on said shield for securing the latter in 125 wearing position.

6. In a combination garment of the class described, a utility seat comprising horizontal edges separable along the center line thereof and normally concealed entirely between the limbs of the wearer, a suspended shield integral 130 at one end with the waist line of the garment and detachable at its other end, fastening means on the garment and on the shield for securing the latter to the garment crotch and for fastening said edges together to conceal said shield, and 135 means for adjustably suspending the free end of the shield upon the wearer's body.

7. In a combination garment of the class described, a utility seat comprising edges separable along a horizontal center line thereof and nor-

- 5 mally concealed entirely between the limbs of the wearer, a suspended back, front and crotch shield integral at one end with the waist line of the garment and detachable at its other end, fastening means for securing the shield to the garment crotch and for fastening said edges to conceal said shield, and waist encircling means for adjustably supporting the free end of the shield upon the wearer's body at the waist line.
- 10 8. In a combination garment of the class described, a utility seat formed with an approximately horizontal central slit, and including an interior shield having downwardly tapering front

and rear portions, the rear portion thereof being cut fuller and wider than the front portion and the upper edges of both extending partially about the wearer's waist, a lateral crotch seam permanently attaching said front and rear portions, means on said lateral crotch seam detachably securing the shield to the garment crotch, a belt attached to said shield for suspending said rear portion, fastening means on said belt, and means on the exterior of the garment adjacent the sides thereof for securing the ends of the belt when said fastening means is disengaged.
